Wesley Libbey ATTORNEY

UNITED STATES PATENT OFFICE

RAY P. HIGBEE, OF PHILADELPHIA, PENNSYLVANIA, ASSIGNOR TO WESTINGHOUSE ELECTRIC & MANUFACTURING COMPANY, A CORPORATION OF PENNSYLVANIA

SAFETY DEVICE FOR ELEVATORS

Application filed May 3, 1928. Serial No. 274,765.

My invention relates generally to safety devices for elevators and more particularly to safety devices for preventing falling of elevator cars.

5 The object of the invention, generally stated, is the provision of a safety device that shall be simple and efficient in operation and adapted for ready and economical manufacture and installation.

10 A more specific object of my invention is to provide for a prompt application of the gripping jaws of the safety device to the guide rails when the downward speed of the elevator car exceeds a predetermined limit.

15 Another object of my invention is to provide for applying a predetermined initial pressure to the gripping jaws of the safety device when the device is actuated to stop the car, the initial pressure to have a value 20 calculated to be sufficient to stop the car under normal loads.

25 A further object of the invention is to provide for cushioning the initial pressure applied to the gripping jaws of the safety device.

30 It is also an object of my invention to provide for applying an additional pressure to the gripping jaws when the initial pressure applied thereto is not sufficient to stop the car.

35 The invention, as disclosed in the accompanying drawing, comprises the structural devices and the combination of elements and arrangements of parts which will be hereinafter set forth and particularly defined in the claims.

40 For a fuller understanding of the invention, reference may be had to the following detailed description, taken in connection with the accompanying drawing, in which:

45 Figure 1 is a diagrammatic representation of the platform of an elevator car provided with a safety device constructed in accordance with my invention.

Fig. 2 is a diagrammatic representation of a modification of the invention illustrated in Fig. 1, and

50 Fig. 3 is an enlarged top plan view, partially in section, of the safety drum em-

bodied in the safety device illustrated in Figs. 1 and 2.

In the drawing, I have illustrated the platform of an elevator car 1 as mounted between a pair of guide rails 2 and 3 and provided with a safety device having two pairs of cooperating safety jaws 4, 5, 6 and 7 for gripping the guide rails when the safety device is actuated. The safety jaws 4, 5, 6 and 7 constitute integral parts of, and are operated by, two pairs of cooperating bell-crank levers 9, 10, 11 and 12, that are pivotally mounted on the underside of the car floor or frame 1 by means of pivotal supports 13, 14, 15 and 16. The outer ends 65 of the bell-crank levers 10 and 12, associated with the jaws 5 and 7 on the one side of the guide rails, are connected and held in operative positions by a pair of push rods 17 and 18, while the cooperating 70 bell-crank levers 9 and 11, associated with the jaws 4 and 6 on the other side of the guide rails, are connected and held in operative positions by a pair of push rods 19 and 20.

75 In order that the safety jaws 4, 5, 6 and 7 may be actuated to grip the guide rails 2 and 3 when the downward speed of the car 1 exceeds a predetermined limit, a safety drum 21, is disposed between the inner ends 80 of the push rods 19 and 20 for the purpose of moving the rods outwardly. The safety drum 21 is mounted on a frame 22 (see Fig. 3) and is provided with a right-hand screw-threaded member 26 that engages a cooperating threaded portion 27 of a pressure-transmitting member 28 mounted on the inner end of the push rod 20, and a left-hand screw-threaded member 29 that engages a cooperating threaded portion 30 on the push 85 rod 19. The pressure-transmitting member 28 is provided with a separate sleeve portion 31 that fits over the ends of the push rod 20 and is secured against rotation thereon by means of a friction clamp 32, for the purpose that will be hereinafter explained.

Inasmuch as the outer ends of the push rods 19 and 20 are square and are disposed in square holes, provided in the bell-crank levers 9 and 11, the rods will be prevented 100

from rotating and will be moved away from each other longitudinally when the screw-threaded members 26 and 29 are turned on the threaded portions 27 and 30 by the rotation of the safety drum 21.

5 The means for rotating the safety drum 21 to operate the push rods comprises a tail rope 35, one end of which is wound around, and secured, to the safety drum and the 10 other end of which is disposed over a pair of guiding sheaves 36 and 37, on the underside of the car platform 1, and is secured to a governor cable (not shown). Inasmuch as governor cables are old and well-known 15 in the art, a description thereof will be omitted.

As shown, the safety drum 21 is provided with a bevelled gear 38 on its right-hand end by means of which it may be reset by 20 any suitable resetting tool (not shown) after it has been operated by the movement of the tail rope 35.

Referring to Fig. 1 of the drawing, in order that the running clearance between the 25 safety jaws 4, 5, 6 and 7 and the guide rails 2 and 3 may be rapidly reduced and the jaws be caused to grip the guide rails as soon as possible after the operation of the safety device, the screw-threaded member 26 30 and the cooperating worm 27 are constructed with a relatively high pitch so that the first few turns of the safety drum 21 will effect a rapid longitudinal separation of the push rods 19 and 20.

35 For the purpose of providing a means for cushioning the initial gripping action of the jaws on the guide rails and also to provide for the application of a predetermined initial pressure to the jaws, a resilient member, such as a compression spring 39, is disposed between a pair of spring seats 40 and 41 that are mounted on the inner ends of the push rods 17 and 18. It will generally be found desirable to make the spring 39 of 40 such strength that it will normally hold the inner ends of the rods 17 and 18 a short distance apart but which will, when compressed to a point where the ends of the push rods meet, exert a sufficient pressure through 45 the push rods, the bell-crank levers and the safety jaws to stop the car.

The frictional clamp 32 that is mounted on the power-transmitting member 28 is 50 provided for the purpose of preventing that member from rotating with the safety drum 21 until the pressure between the threads on the members 26 and 27 reaches such a degree that the friction caused thereby overcomes the frictional engagement of the 55 clamp and causes the pressure-transmitting member 28 to rotate with the safety drum 21. In the present case, the frictional engagement of the clamp 32 is designed to be 60 overcome at the point when the spring 39 is compressed to such degree that the inner 65

ends of the cooperating push rods 17 and 18 engage each other and cause a positive pressure to be exerted on the safety jaws 4, 5, 6 and 7.

In the modification of the invention illustrated in Fig. 2, the spring 39a is so disposed on the push rods 17 and 18 that it will, unless compressed, close the safety jaws 4, 5, 6 and 7 on the guide rails 2 and 3 with sufficient pressure to stop the car. Therefore, in this modification of the invention, an electromagnet 42 is mounted on the inner 70 ends of the cooperating push rods 17 and 18 in conjunction with the spring 39a to pull the rods together against the compression 75 of the spring and thereby maintain a running clearance between the jaws and the guide rails. One end of the electromagnet 42 is firmly secured to the rod 17 while its other end surrounds the inner end of the 80 rod 18 and engages the spring 39a and compresses it against the spring seat 41a on the push rod 18.

A suitable supply of electrical energy for 85 energizing the electromagnet 42 is provided by connecting the magnet, through a pair of conductors 43 and 44, a switch 45, and a conductor 46, to line conductors L1 and L2. The switch 45 is controlled by the safety 90 governor 47 in such manner that the downward operation of the car 1 at an excessive speed will cause the governor to open the switch and thereby deenergize the electromagnet 42.

95 It should be noted that, with the safety device arranged either as shown in Fig. 1 or in Fig. 2, it is necessary to provide for a small transverse movement of the car 1 with reference to the guide rails 2 and 3 for the purpose of permitting full cooperation of 100 the safety jaws 4, 5, 6 and 7.

The operation of the safety device, as arranged in Fig. 1, is as follows: Assuming 105 that the car, in traveling downward, exceeds a predetermined speed limit, it will, through 110 the action of the safety governor 47 and the governor cable (not shown), exert a pull on the tail rope 35 which will, in turn, rotate the safety drum 21. The rotation of the safety drum 21 will, through the action 115 of the high-pitch screw-threaded member 26 and the lower-pitch screw-threaded member 29, cause the push rods 19 and 20, to rapidly move outward from the drum and push against the outer arms of the bell-crank levers 9 and 11. The pressure of the 120 push rods 19 and 20 against the bell-crank levers 9 and 11 will, with the cooperating action of the spring 39, the push rods 17 and 18 and the bell-crank levers 10 and 12, 125 cause the safety jaws 4, 5, 6 and 7 to grip the guide rails 2 and 3. The rotation of the safety drum 21 will be continued by the action of the falling car, in pulling on the tail rope 35, until the pressure exerted 130

on the safety jaws is sufficient to stop the car. Under ordinary circumstances, the initial pressure, as determined by the spring 39, will be sufficient to stop the car when 5 operating at such speed as will trip the governor, and when normal loads are carried by the car. However, if this pressure is not sufficient to stop the car and the car continues downward, the safety drum 21 will 10 continue to rotate and increase the closing pressure on the jaws 4, 5, 6 and 7.

As the pressure increases, the spring 39 will be compressed to a point where the inner ends of the push rods 17 and 18 engage 15 each other and cause a positive application of the closing pressure to the safety jaws. At this stage of the operation, the pressure between the high-pitch screw-threaded member 26 and the screw-threaded 20 worm 27 on the power-transmitting member 28 will create sufficient friction to overcome the frictional engagement of the clamp 32 and cause the member 28 to rotate with the safety drum 21. When the member 25 25 rotates with the safety drum 21, the additional spreading pressure is effected by the drum through the low-pitch member 29, and the action continues at the low speed of the member 29 until the car stops.

30 The operation of the modified form of the device illustrated in Fig. 2 is practically the same as that shown in Fig. 1 except that the setting of the safety governor 47 by an excessive downward speed of the car 35 will open the switch 45 and deenergize the electromagnet 42. The deenergization of the electromagnet 42 releases the push-rod 18 and permits the spring 39a to effect a closing movement of the safety jaws 4, 5, 40 6 and 7. At the same time, the safety drum 21 starts to rotate and applies an additional closing pressure to the jaws through the outward movement of the push rods 19 and 20. If the car is not stopped by the pressure 45 applied through the initial expansion of the spring 39a, the safety drum will continue to rotate until the spring is compressed to such a point that the inner ends of the push rods 17 and 18 engage each other and 50 cause a positive pressure to be applied to the jaws. If the car is not stopped by the pressure applied at this stage of the operation of the safety device, the further descent of the car continues the rotation of the 55 safety drum 21 and applies additional positive closing pressure to the jaws until the car comes to rest.

When it is desired to reset the safety device after it has operated to stop the car, 60 any suitable resetting tool (not shown) may be employed to engage the gear teeth 38 on the safety drum 21 and rotate it to release the safety jaws 4, 5, 6 and 7 and rewind the tail rope 35 on the drum.

65 It will, therefore, be seen that I have de-

vised an improved safety device that provides for the prompt application of an initial cushioned retarding force upon the operation of the safety governor; that I have provided for limiting the initial retarding force to a predetermined value, and that I have provided for the application of an additional retarding force when the initial predetermined retarding force does not stop the car. It will also be noted that my improvement provides for a rapid application of the initial retarding force and a slower application of such additional retarding force as may be necessary to stop the car. 70 Since various modifications and changes may be made in the devices illustrated herein as embodying my invention without departing from the spirit and scope thereof, all such modifications and changes are intended to be covered by the appended claims. 75

I claim as my invention:

1. In a safety device for an elevator, a plurality of safety jaws mounted on the car for gripping the guide rails, a pair of levers for operating said jaws, and a safety drum for actuating said levers, said drum being connected to one lever by a high-pitch screw thread and to the other of said levers by a lower-pitch screw thread. 90

2. In a safety device for an elevator, a plurality of safety jaws mounted on the car for gripping the guide rails, a pair of levers for operating said jaws, a safety drum for actuating said levers, said drum being connected to one lever through a high-pitch screw thread and to the other lever through a lower-pitch screw thread, and means for cushioning the gripping action of the jaws while being operated through the high-pitch screw thread. 95

3. In a safety device for an elevator, a plurality of safety jaws mounted on the car for gripping the guide rails, a pair of levers for operating said jaws, a pressure-transmitting member in frictional engagement with one of said levers, and a safety drum having a high-pitch screw thread for actuating the pressure-transmitting member to move the lever which it engages, and a low-pitch screw thread for operating the other of said levers, the frictional engagement between the member and the lever actuated by it being of such degree as to be overcome by the frictional engagement of the high-pitch screw thread and thereby prevent further relative longitudinal movement between the drum and the member. 110

4. In a safety device for an elevator, a plurality of safety jaws mounted on the car for gripping the guide rails, a plurality of cooperating levers for operating said jaws, a spring for biasing said jaws toward a closing position, a safety drum for applying positive pressure to said levers, and a pressure-transmitting member disposed be- 125

130

tween the drum and one of said levers, said member being connected to said lever by a frictional engagement sufficient to prevent the rotation of the member on the lever until the pressure of the biasing spring is overcome.

5. In a safety device for an elevator, a plurality of safety jaws mounted on the car for gripping the guide rails, a plurality of cooperating levers for operating said jaws, a spring for biasing said jaws toward a closing position, a safety drum for applying positive pressure to said levers, and a pressure-transmitting member disposed between the drum and one of said levers, said member being operated by said drum through a screw-threaded connection and being in frictional engagement with its corresponding lever, and said frictional engagement being sufficient to cause said member to be moved longitudinally by said drum through the screw-threaded connection until the compression of the spring is overcome.

25. In a safety device for an elevator, a plurality of safety jaws mounted on the car for gripping the guide rails, an electromagnet for retaining said jaws in an open position, an electric circuit controlled by the safety governor for energizing said electromagnet, a spring for actuating said jaws to a closed position when the magnet is deenergized, means for applying additional pressure to said jaws through said spring, and means for applying additional positive pressure to said jaws upon further movement of the car.

40. In a safety device for an elevator, a plurality of safety jaws mounted on the car for gripping the guide rails, an electromagnet for retaining said jaws in an open position, an electric circuit controlled by the safety governor for energizing said electromagnet, a spring for applying a closing pressure to said jaws when the magnet is deenergized, means for rapidly applying additional pressure to said jaws through said spring, and means for less rapidly applying additional positive pressure to said jaws upon further movement of the car.

55. In a safety device for an elevator, a plurality of safety jaws mounted on the car for gripping the guide rails, an electromagnet for retaining said jaws in an open position, an electric circuit controlled by the safety governor for energizing said electromagnet, a spring for applying a closing pressure to said jaws upon deenergization of the electromagnet, a safety drum for applying additional closing pressure to said jaws, a pressure-transmitting member for connecting the drum to the jaws through a frictional engagement, said frictional engagement being calculated to become inoper-

ative upon the application of a predetermined pressure to the spring.

In testimony whereof, I have hereunto subscribed my name this 16th day of April, 1928.

RAY P. HIGBEE.
